UNITED STATES PATENT OFFICE.

CHARLES H. PROCTOR, OF SHEBOYGAN, WISCONSIN.

FOLDING BERRY-BOX.

1,223,202.

Specification of Letters Patent. Patented Apr. 17, 1917.

Application filed July 13, 1916. Serial No. 109 114.

To all whom it may concern:

Be it known that I, CHARLES H. PROCTOR, a citizen of the United States, residing at Sheboygan, in the county of Sheboygan and 5 State of Wisconsin, have invented certain new and useful Improvements in Folding Berry-Boxes; and I do declare the following to be a full, clear, and exact description of the invention, such as will enable others 10 skilled in the art to which it appertains to make and use the same.

This invention relates to new and useful improvements in boxes, and more particularly to boxes adapted for shipping berries 15 and other small fruit, and has for its principal object to provide a box which is easily folded for shipment so that a large number will occupy a very small space and which can be quickly put into shape for use without 20 having to perform any additional operation except the unfolding thereof, and which when in use, will be very strong and efficient so it is adapted for extensive and continued use.

Formerly in the manufacture of boxes of 25 this character, they were made up in sections and shipped to the farmers, and it was necessary for the farmer to employ a stapling machine to assemble the various parts of the 30 boxes. This was very expensive to small producers that only shipped small quantities of fruit such as berries, and one of the objects of the present invention is to so construct a box of this character that it is assembled and folded when shipped to the 35 farmer and it is not necessary for him to perform any additional work thereon other than unfolding before the box may be used.

A further object of the invention is to 40 provide a device of this character which is simple and durable in construction, inexpensive to manufacture, and one which will be very efficient in operation.

With these and numerous other objects in 45 view, my invention resides in certain novel features of construction, and the combination and arrangement of parts which will hereinafter be more particularly described and claimed.

In the accompanying drawings:

Figure 1 is a perspective view showing my improved box folded;

Fig. 2 is a similar view showing the box open, but with the bottom flap upright and 55 not yet in position;

Fig. 3 is a perspective view partly broken

away showing the box completely in folded position;

Fig. 4 is a transverse section;

Fig. 5 is a section taken on the line 5—5 of Fig. 4; and

Fig. 6 is a top plan view of the box locked in open position.

In describing my invention I shall refer to the drawings in which similar reference characters designate corresponding parts throughout the several views. This box comprises a strip of wood such as veneer or other suitable material which has transverse V-shaped scores 1 at predetermined intervals along 65 one side, so as to allow the strip to be bent at right angles at said scores to form corners of a rectangular shaped box which is formed when the strip is bent. The strip will be divided into five parts by the four 70 transversely extending scores 1 which parts are designated by the numerals 2, 3, 4, 5 and 6 and the ends 2 and 6 of the strip are overlapped and are fastened together by suitable metal staples 7. When in this position, the rectangular shaped box will be 75 formed which is, owing to the scored corners, adapted to be compressed to the flat parallelogram shape when it is desired to fold the same for shipment.

The bottom for the box is formed by a strip 8 of the same kind of material as the box, and which has two V-shaped score marks 9 and 10 made across it, adjacent the ends 11 and 12 of the same. The upper free 80 end 12 of the bottom is cut away at each corner as plainly shown in Fig. 1 of the drawings, and the bottom strip 8 is secured to the inner lower face of the wall 2 of the box at the other end 11 by additional staples 85 13 which hold the bottom permanently to the box. The end sections of the strip 8 are adapted to be bent downwardly, the section 11 being secured to the wall 2, while the 90 downwardly bent outer free end 12 is so 95 positioned for the purpose to be hereinafter more fully described.

The lower inner surface of the wall 4 of the box has secured thereto a locking strip 14 by means of staples 15 which project through the said strip and through the wall adjacent the lower edge of the same. This locking strip 14 is made of the same material as the box 1, and owing to the fact that the lower edge of the same is secured 105 adjacent the lower edge of the wall 4, its 110 upper edge is adapted to be slightly flexible

so that it may be moved outwardly from the wall to receive the downturned free end 12 of the bottom 8 when the box is in open position. This will securely lock the bottom of the box so that the same may be used for the ordinary purposes.

It is evident that, when the bottom has been raised to the position shown in Fig. 2 of the drawings, the sides or walls of the box can be compressed together out of rectangular form into the flat or parallelogram form shown in Fig. 1 of the drawings, and that when in this form, a large number may be easily shipped as they will 15 occupy a very small space. When it is desired to use the boxes, each box is drawn out into rectangular shape and the free end 12 of the bottom strip 8 is bent at right angles so that when the bottom strip 8 is bent into 20 the box, the free end 12 will pass between the upper portion of the strip 14 and the adjacent wall 4 of the box. The box will then be securely held in open position and ready for use.

25 From the foregoing description of the construction of my improved folding berry box, the use and operation thereof will be readily understood and it will be seen that I have provided a very simple and efficient 30 means for carrying out the objects of this invention. Attention is particularly called to the securing strip 14 that removably and securely locks the bottom in the box, when the box is in open position. This locking 35 strip is formed of the same material as the box and is very simply and easily manufactured during the manufacture of the other parts of the box. All the different parts shown and described are assembled at the 40 factory before shipment, and when shipped, by the above simple operation, the box is easily opened and locked in open position.

The scores used to form the corners and also on the bottom strip of this device, are

made by a V-shaped knife which merely 45 plows a shallow furrow in the veneer without cutting deeply, so that the box will not become weakened at the hinged points. Where the scoring is done with a straight knife, the furrow is often cut almost 50 through the veneer, thus making the box weak at the corners and resulting in the breakage of the same in a very short while.

I claim as my invention:

In a folding berry box, the combination 55 with a thin wooden strip having four transverse V-shaped scores therein dividing it into five portions, four successive portions being of equal size and the remaining end portion being smaller, said strip being 60 adapted to be folded with its smaller end portion overlapping the larger end and secured thereto adjacent one edge to form a substantially rectangular box adapted to be compressed to flat parallelogram shape, a 65 substantially rectangular-shaped wooden bottom strip with transverse V-shaped scores adjacent two of its opposite edges, said edges being bent downwardly at right angles to the bottom strip, one of the edges 70 being secured to the inner end wall of the box strip adjacent its bottom, a separate wooden locking strip secured at its ends across the lower inner side of the opposite wall of the box, and the free bent edge of 75 the bottom strip having its corners cut away whereby said end is adapted to pass between the upper end of the locking strip and the adjacent wall of the box to hold the box securely in open position.

80 In testimony whereof I have hereunto set my hand in the presence of two subscribing witnesses.

CHARLES H. PROCTOR.
